Patented May 21, 1918.

UNITED STATES PATENT OFFICE.

LAWRENCE E. CONNELLY, OF CLEVELAND, OHIO.

STEAM-GENERATOR.

1,266,664.

Specification of Letters Patent.

Patented May 21, 1918.

Application filed October 15, 1917. Serial No. 196,650.

To all whom it may concern:

Be it known that I, LAWRENCE E. CONNELLY, a citizen of the United States, residing at Cleveland, in the county of Cuyahoga and State of Ohio, have invented certain new and useful Improvements in Steam-Generators; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to steam generators and particularly to that class of steam generators known as water tube generators.

The objects of my invention are to so construct a water tube steam generator that the steam may be withdrawn from a drum in which the water is still, and also in such a manner that the water tubes which are exposed to the direct action of the heat are straight.

In my improved generator I provide a pair of box-like tube headers which are connected by the main series of water tubes, the said headers being so arranged that the tubes are inclined upwardly in the direction of the flow of water therethrough. Transversely above the intermediate portion of said tubes is a steam-liberating drum, which is directly connected with the upper portion of each header by means of series of water tubes, and above the lower header I place a feed-water receiving drum, which is connected with said lower header by means of water tubes, and with said steam-liberating drum by means of a series of steam conveying tubes.

These and other features of my invention are fully described and pointed out hereinafter, and are illustrated in the accompanying drawings, in which:—

The figure is a vertical central section of a steam generator embodying my invention.

In this drawing A and A' indicate box-headers, the header A' being placed higher in the setting than the header A, and both headers being inclined forwardly so that the series of straight water tubes B will be at right angles thereto. The outer plate b of each header is provided with openings opposite the ends of the water tubes, through which access can be had thereto,

which openings are closed with screw plugs b', or in any other manner which may be deemed more desirable.

Above the tubes B is a transverse steam-liberating drum C, which is connected to the header A' by means of a series D of steam and water conveying tubes; and said drum is also connected with the header A by means of a series D' of downflow water tubes.

In front of the drum C, and over the header A, I place another drum E, which is connected with the header A by means of downflow water tubes e, and also is connected with the drum C by means of a series F of steam conveying tubes. E' indicates a steam-line connection which communicates with the drum E. E² indicates a feed-water pipe by means of which feed-water is supplied to the drum E, and thence through the downflow tubes e to the header A. G indicates the smoke exit from the boiler setting, and G' indicates the cover thereof.

Under the header A I place a small mud-receiving drum H which is connected therewith by means of a series of tubes h, and said mud-drum is provided with a blow-off tube and valve h'. J indicates the furnace chamber above the fire grate J'. K, K', K², K³, and K⁴ are baffle walls so arranged as to cause the fire-gas in its hottest state to impinge upon the water tubes B at that portion thereof wherein the upwardly flowing water is the hottest; and thereafter, as the fire-gas becomes reduced in temperature, it impinges with portions of said tubes wherein the water is of lower temperature. This is a very desirable feature in a steam generator because the higher the degree of heat within the tubes, the higher must be the heat on the outside of the tube to effect a transfer of heat from the outside to the inside of such tubes.

In operation the generator is filled until the water reaches the level indicated by the broken line x—x; then as the water becomes heated, it flows upwardly through the tubes B, header A' and tubes D into the drum C wherein steam is liberated and flows therefrom through the series F of steam conveying tubes into the feed-water receiving drum E, from whence it is withdrawn for use through the connection E'.

The steam, during its passage through the series of tubes F is somewhat dried out

5 by reason of said tubes being located in a sort of oven space between the drums C and E, through which the fire-gas passes prior to reaching the smoke exit G. The residue 10 of water which does not turn to steam in the drum C flows downwardly therefrom through the series of tubes D' into the header A. The supply of water in the generator is kept replenished through the feed-water supply pipe E² and drum E. It will 15 thus be seen that the steam from my improved generator is withdrawn from the feed-water receiving drum wherein there is little or no agitation, after said steam has 20 been partially dried during its passage through the tubes F. It will also be observed that in this form of construction I can use straight tubes where the furnace heat is most intense, and that said tubes are 25 easy of access and can be easily repaired should occasion therefor arise.

Having thus fully shown and described my invention so as to enable others to utilize the same, what I claim as new and desire 25 to secure by Letters Patent, is:—

1. In a steam generator of the class described a pair of box-like headers, one of which is placed at a higher elevation than the other, a series of inclined water tubes 30 connecting said headers, a transverse steam liberating drum above said inclined tube, a series of steam and water conveying tubes connecting the upper portion of the higher of said headers with said drum, and a series 35 of down-flow water tubes connecting the

lower portion of said drum with the upper portion of the lower header, another transverse steam and feed-water receiving drum over the lower header, means to connect the said steam and feed-water receiving drum with said lower header, and a series of steam conveying tubes connecting the upper portions of said steam liberating drum and said steam and feed-water receiving drum, substantially as set forth. 40

2. In a steam generator of the class described, a box-like header at the front thereof, another box-like header at the rear thereof and at a higher elevation, a series of inclined tubes connecting said headers, a transverse steam liberating drum located over the intermediate portion of said inclined tubes, a series of steam and water-conveying tubes connecting the upper portion of said rear and higher header with said steam liberating drum, a series of down-flow water tubes connecting the lower portion of said liberating drum with the upper portion of said front and lower header, a steam and feed-water receiving drum located on the line of 50 the water level of said generator and above said front and lower header, a series of steam conveying tubes connecting the upper portions of said liberating drum and said steam and feed-water receiving drum, and means to connect the lower portion of said steam and feed-water drum with said front and lower header, substantially as set forth. 55

In testimony whereof I affix my signature.
LAWRENCE E. CONNELLY.
